UNITED STATES PATENT OFFICE

ABRAHAM MOSCOWITZ, OF JERSEY CITY, NEW JERSEY

DETERGENT

Application filed October 24, 1929. Serial No. 402,313.

No Drawing.

This detergent contains a mixture of the potassium and triethanol amine soaps of fatty acid. The total quantity of soaps present calculated as dry soaps may vary between 50 and 70 per cent by weight of the detergent viz, between 50 and 70 per cent by weight of the total soaps, water and alcohol composing the finished detergent. The triethanol amine soap of fatty acid is present to the extent of 40 to 75 per cent of the total soaps, dry basis viz, to the extent of 40 to 75 per cent of the actual soaps present in the mixture excluding free water and alcohol. Water is present to the extent of at least 4 per cent of the total detergent and the balance consists of an alcohol containing not exceeding three carbon atoms to the molecule. While the alcohol may be methyl, ethyl, and either normal propyl or iso-propyl, I prefer the use of ethyl alcohol for this purpose. While I may employ a variety of fatty acids or mixtures thereof in forming the soaps above mentioned, and such mixtures shall be herein-after comprehended within the term "fatty acids", I preferably employ the potassium and triethanol amine soaps of commercial oleic acid.

Where the soaps employed are the compounds of potassium and triethanol amine with oleic acid, if the per cent of water present does not substantially exceed 4 per cent and the balance of the mixture is alcohol, the detergent will be optically transparent at normal temperatures. If, however, soaps comprising other fatty acids than oleic acids are employed within the proportions hereinabove mentioned and within the ratios of potassium to triethanol amine soap hereinbefore defined, the fatty acid must be so selected that with 4 per cent of water present and the balance of the mixture consisting of alcohol the detergent will be optically transparent at normal temperatures. For any selected content and composition of dry soaps the per cent of water may be further increased and the per cent of alcohol decreased, provided, however, that the amount of water added is not sufficient to produce a detergent which is not optically transparent. I find the optical transparency to be related to the speed and

completeness of the dispersion of the soap in organic solvents and the effectiveness thereof. It will be seen, therefore, that while a minimum of 4 per cent of water is necessary, the proportions of water and alcohol for any selected soap content are susceptible of variation within certain limits.

My detergent may be made by mixing the constituent materials or by combining the bases either separately or collectively with the necessary amount of fatty acid, preferably in the presence of the requisite amount of alcohol needed to form the finished mixture, and preferably thereafter adding such amount of water as is necessary to create a product of the defined composition.

The new composition is applicable for use either in aqueous solution or in solution in organic solvents as practiced in dry cleaning art. A small proportion of the detergent added in either case produces a marked diminution in surface tension of the solvent and enhanced cleansing properties. In particular, where small amounts of this detergent are added to organic solvents such as cleaner's naphtha, exceptional cleansing properties are imparted. In this case, moreover, the solution of organic solvent containing my detergent appears to possess the capacity to penetrate and remove from the garments, to be cleaned, impurities of both water and oil soluble nature.

Where the organic solvent (cleaner's naphtha for example) is purified subsequent to use by filtration, for example, filtration thru a plate and frame filter under pressure, my detergent has proved singularly efficacious in permitting free filterability and a maximum throughput for the filter before cleaning the same becomes necessary.

I claim:

1. A detergent comprising 50 to 70 per cent, dry basis, of the potassium and triethanol amine soaps of acids selected from the fatty acids, between 40 to 75 per cent of the total soaps present, dry basis, being the triethanol amine soap of the selected fatty acids, not less than 4 per cent of water, and an alcohol of not exceeding three carbon atoms in

amount sufficient to render the detergent optically transparent.

2. A detergent comprising 50 to 70 per cent, dry basis, of the potassium and tri-
ethanol amine soaps of acids selected from
the fatty acids, between 40 to 75 per cent of
the total soaps present, dry basis, being the
triethanol amine soap of the selected fatty
acids, not less than 4 per cent of water, and
ethyl alcohol in amount sufficient to render
the detergent optically transparent.

3. A detergent comprising 50 to 70 per
cent, dry basis, of the potassium and tri-
ethanol amine soaps of oleic acid, between
40 to 75 per cent of the total soaps present,
dry basis, being the triethanol amine soap of
oleic acid, not less than 4 per cent water, and
an alcohol of not exceeding three carbon
atoms in amount sufficient to render the deter-
gent optically transparent.

4. A detergent comprising 50 to 70 per
cent, dry basis, of the potassium and tri-
ethanol amine soaps of oleic acid, between
40 to 75 per cent of the total soaps present,
dry basis, being the triethanol amine soap
of oleic acid, not less than 4 per cent of water,
and ethyl alcohol in amount sufficient to
render the detergent optically transparent.

ABRAHAM MOSCOWITZ.
